GRINDING MACHINE

Carl G. Flygare, Worcester, Mass., assignor to
 Norton Company, Worcester, Mass., a corpora-
 tion of Massachusetts

Application October 15, 1938, Serial No. 235,122

1 Claim. (Cl. 191—12)

This invention relates to grinding machines, and more particularly to a large cylindrical grinding machine.

One object of the invention is to provide a simple and thoroughly practical precision grinding machine such as a large roll grinding machine having a massive reciprocable table for supporting a work piece or the rotatable grinding element. A further object of the invention is to provide a large cylindrical grinding machine having a reciprocable table upon which are mounted a plurality of electric motors, with a power transmitting mechanism for conveying electric current to the motors on the table during reciprocation of the same. A further object of the invention is to provide an improved electric power transmitting mechanism for conveying electric current to a motor or motors on a reciprocable table. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claim.

In the accompanying drawings, in which is shown one of various possible embodiments of the mechanical features of this invention.

Fig. 1 is a front elevation of a roll grinding machine of the wheel traverse type showing the improved electric power transmission mechanism;

Fig. 2 is a fragmentary elevation, on an enlarged scale, of the electric power transmitting mechanism;

Fig. 3 is a fragmentary elevation, on an enlarged scale, of the cable carrier and the power transmission mechanism;

Fig. 4 is a fragmentary cross sectional view, on an enlarged scale, taken approximately on the line 4—4, showing the grooved pulleys for supporting a plurality of power transmitting cables;

Fig. 5 is a fragmentary sectional view, on an enlarged scale, taken approximately on the line 5—5 of Fig. 3, showing the idler pulley for supporting the cable supporting belt; and

Fig. 6 is a schematic electric wiring diagram of the machine.

This invention is particularly applicable to a large massive cylindrical grinding machine for grinding large rolling mill rolls and the like which may be either one of two types, namely, a work traverse type machine or a wheel traverse type machine. In either case the work piece is supported on centers and steadied by journal rests

while either the work support or the grinding wheel support is reciprocated longitudinally to produce a relative longitudinal reciprocatory movement between the grinding wheel and work piece to grind the peripheral surface thereof.

A cylindrical grinding machine of the wheel traverse type has been illustrated in the drawings comprising a base 10 which supports a longitudinally reciprocable grinding wheel carriage 11 on the usual V-way and flat way (not shown). The longitudinally reciprocable grinding wheel carriage 11 serves as a support for a transversely movable wheel slide 14. The wheel slide 14 supports a rotatable wheel spindle having a grinding wheel 15 on its outer end which is partially surrounded by a wheel guard 16. A power driven mechanism is provided for rotating the grinding wheel 15 comprising an electric motor 17 which is mounted on the upper surface of the wheel 20 slide 14. The motor 17 is connected to rotate the wheel spindle by means of a multiple V-belt drive 18 contained within a guard 19 supported on the wheel slide 14.

A suitable power operated grinding wheel carriage reciprocating mechanism (not shown) is provided to reciprocate the grinding wheel 15 longitudinally. This mechanism has not been illustrated in the present case since it is not considered to be part of the present invention. This mechanism may be of the type shown in the prior patent to Norton No. 1,096,188 dated May 12, 1914, to which reference may be had for details of disclosure of the wheel reciprocating mechanism not found herein. The wheel carriage reciprocating mechanism is contained within a housing 25 supported on the upper surface of the longitudinally reciprocable wheel carriage 11. A manually operable wheel 26 is provided whereby the carriage 11 may be manually adjusted, if desired. During the normal operation of the machine, the wheel carriage reciprocating mechanism is power driven by means of an electric motor 27 mounted on the upper surface of the housing 25. The motor 27 is connected by means of a belt drive contained within a belt guard 28 to drive the wheel carriage reciprocating mechanism.

A feeding mechanism is provided for producing a relative transverse movement between the grinding wheel and the work piece to grind the work to the required and predetermined size. In the present case, as illustrated, the wheel slide 14 is mounted for a transverse feeding movement relative to the table 11. This is preferably ac-

complished by means of a wheel feeding mechanism contained within a casing 30, said mechanism being driven by means of an electric motor 31 mounted on the upper surface of the longitudinally reciprocable carriage 11.

The work piece to be ground is supported by means of a headstock 35 and a footstock 36 which are fastened to a swivel table 37 which is in turn adjustably fixed on the base 10 of the machine. 10 The work piece is rotatably supported by means of a headstock center (not shown) and a footstock center 38 for rotation in operative relation with the grinding wheel 15. The headstock 35 is preferably motor driven by an electric motor 15 40 mounted on top of the headstock 35. The motor 40 is connected by means of a multiple V-belt drive contained within a belt guard 41 to rotate the headstock spindle (not shown) to rotate the work piece for a grinding operation.

20 A machine of the type illustrated in the drawings is particularly designed and intended for grinding work pieces up to forty feet or more in length and one foot or larger in diameter. In such a machine with a table reciprocatory stroke 25 of forty feet, more or less, it is desirable to provide an electric power conveying means so that during the reciprocatory stroke of the table or wheel carriage 11, electric current may be transmitted to the electric motors 17, 27 and 31. In order to attain the primary object of this invention, it is desirable to provide an improved electric power transmitting means whereby with a minimum length of electric cable, electric power may be conveyed to the reciprocating table during its entire maximum length of stroke. Power is transmitted to the machine from any suitable source by means of a cable 50 to a junction box 51 which is fixedly mounted at the right hand end of a channel iron 52. The channel iron 52 30 is supported by brackets 53, 54, 55, 56 and 57 which are fixedly supported on the base 10. The inner area of the channel iron 52 is covered with strips of insulating material, such as a wood base 58 and side strips 59 and 60 (Figs. 4 and 5). This insulated area within the channel iron 52 serves as a trough to support electric power cables 65, 66, 67, 68, 69 and 70. The cables 65 to 70 inclusive have one of their ends fixedly connected within the electric junction box 51 (Figs. 1 and 2) 35 and are connected therein to the power cable 50. The cables 65 to 70 inclusive extend from the junction box 51 (Fig. 2) along the channel iron trough toward the left and wrap around the peripheries of grooved pulleys 71, 72, a pulley 73, 40 and grooved pulleys 74 and 75. These cables then extend toward the right (Fig. 2) and have their other ends connected by a bracket 76 located at the right-hand end of the longitudinally reciprocable wheel carriage 11 (Figs. 2 and 3). 45 These cables are then connected by means of flexible cables or conduits, such as conduit 77 which is in turn connected through an electric control box 78 to the electric motors 17, 27 and 31, respectively, to transmit power thereto during the longitudinal reciprocatory movement of the carriage 11.

The pulleys 71 to 75 inclusive are rotatably supported on a shaft 80 which is supported on a longitudinally movable cable carrier 81. The cable carrier 81 is provided with spaced pairs of rollers 82 and 83 which ride upon the upwardly extending side walls of the channel iron 52 which serve as guideways for the longitudinally movable cable carrier 31.

75 It is desirable that the cable carrier 81 be

5 moved longitudinally by and in timed relation with the longitudinal reciprocatory movement of the wheel carriage 11 so that when the carriage 11 moves toward the left (Figs. 1, 2 and 3), the cables 65 to 70 inclusive will be laid out and supported on the insulating strips within the channel iron 52. As the carriage 11 moves toward the left, the length of cable between the bracket 76 and the pulleys 71 to 75 inclusive will be increased as the cable is picked up from the trough 10 or channel iron 52. The cable carrier 81 is preferably arranged so that it may travel in the same direction as the carriage 11 and at one-half the speed thereof in order to maintain the cables taut during the entire reciprocatory movement 15 of the carriage 11. The traverse of the cable carrier 81 is preferably accomplished by providing a cable 90 which wraps around an idler pulley 91 20 rotatably supported on a shaft 92 on the cable carrier 81. The upper end of the cable 90 is fastened by means of a bracket 93 to a depending lug 94 on the left-hand end of the longitudinally reciprocable carriage 11. The lower end of the cable 90 is connected by a bracket 95 with a plate 96 which is fastened to the left-hand end of the 25 channel iron 52 (Figs. 1, 2 and 3). It will be readily apparent from the foregoing disclosure that when the grinding wheel carriage 11 is moved toward the left (Figs. 1, 2 and 3), the upper end of the cable 90 is pulled along with the 30 carriage 11. This movement rotates the idler pulley 91 on its supporting shaft 92 and causes an endwise movement of the cable carrier 81 toward the left, in the same direction as and at one-half the speed of the grinding wheel carriage 35 11. When the wheel carriage 11 starts moving toward the right, the cables 65 to 70 inclusive being fixed at their upper ends to the clamping member 76 on the end of the carriage 11 and their lower ends being fixed within the junction 40 box 52 fixed to the base 10, the cables will serve to aid in moving the cable carrier 81 toward the right, that is, in the same direction and at one-half the speed of the grinding wheel carriage 11.

Due to the length of the cables 65 to 70 inclusive, when the carriage 11 is extended to its extreme position toward the right (Fig. 1), it is desirable to provide intermediate supports for the electric power cables so that they will not sag or become stretched during continued movement 45 thereof. As shown in Figs. 1 and 2, idler pulleys or rollers 100 and 101 are rotatably supported on the base of the machine and are of sufficient width to aid in supporting all of the cables 65 to 70 inclusive. In order to supplement the idler 50 rollers 100 and 101, a flexible belt 102 of a width slightly greater than the cables 65 to 70 inclusive is provided. This belt extends over the idlers 100 and 101 and is attached at one end to a clamp 103 which is fixed to the bracket 76 at the right-hand end of the carriage 11. The belt 102 passes around the periphery of a grooved pulley 104 which is rotatably supported on a shaft 105 carried by the cable carrier 81. The lower portion of the belt 102 which wraps around the pulley 104 55 extends toward the right (Figs. 1, 2 and 3) and is adjustably and yieldably connected by means of a spring 106 and a screw 107 to a bracket 108 fixedly mounted at the end of the channel iron 52. By adjusting the screw 107 relative to the 60 bracket 108, the tension of the spring 106 or springs 106 may be varied to tension the belt 102 as desired adequately to support and prevent sagging of the cables 65 to 70 inclusive as the carriage 11 is reciprocated. The belt 102 also aids 65

the cables 65 to 70 inclusive in moving the cable carrier 81 toward the right when the carriage 11 is traversed toward the right.

The operation of this improved electric power transmitting mechanism for motors on reciprocable grinding machine carriages or tables is readily apparent from the foregoing disclosure. Current from a source of supply is fed to the junction box 51 by means of a cable 50. The current then passes through the cables 65 to 70 inclusive which wrap around the pulleys on the cable carrier 81 and have their other ends connected to the bracket 76 at the right-hand end of the carriage 11 from which current is conveyed by conduit 77 to the motors 17, 27 and 31, respectively, to transmit power thereto during the entire reciprocating stroke of the carriage 11.

While a machine of the grinding wheel traverse type has been illustrated in the drawings, this invention is equally applicable to the other common type of grinding machine, namely, the work table traverse type machine in which the rotatable work piece is mounted on the longitudinally reciprocable carriage, such as, for example, that shown in the prior patent to Dunbar No. 1,466,893 dated September 4, 1923.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown

in the accompanying drawings is to be interpreted as illustrative and not in a limiting sense.

I claim:

In a grinding machine having a base, a longitudinally reciprocable carriage thereon, a motor on said carriage, and means for conveying electric power to said motor during longitudinal reciprocation of said carriage including a longitudinally movable power cable carrier, a rotatable idler pulley thereon, a longitudinally extended inverted channel iron fixed to said base, said channel iron serving as a guideway for said carrier, an electric junction box fixedly mounted at one end of said channel iron, a flexible power cable having one end connected to said box, said cable extending along said channel and partially wrapping around said pulley, connections between the other end of said cable and the carriage, a second idler pulley on said carriage, a flexible belt which partially wraps around the latter pulley and has one end fixed to the end of said channel iron and the other end fixed to said reciprocable carriage, said belt serving as a support for the power cable when extended and also serving to move the carrier in one direction during the carriage movement, and independent means including a flexible cable which wraps around a third idler pulley on said carriage and has one end fastened to the carriage and the other to the base actuated by and in timed relation with said carriage to move said carrier longitudinally in the opposite direction and at one-half the speed of the carriage.

CARL G. FLYGARE. 35
